UNITED STATES PATENT OFFICE.

MARTIN A. MIKESCH, OF MILWAUKEE, WISCONSIN, ASSIGNOR TO A. O. SMITH CORPORATION, OF MILWAUKEE, WISCONSIN, A CORPORATION OF NEW YORK.

QUICK-DETACHABLE DAM FOR THE MOLDS OF CENTRIFUGAL CASTING MACHINES.

Application filed November 17, 1924. Serial No. 750,318.

My invention resides in a novel construction whereby the dam or cover for the mouth of a mold used in the centrifugal casting of metals may be quickly attached to the mold and as expeditiously removed therefrom. In the latter aspect of its use, the invention has great value, for the time element becomes an important factor from the moment that the molten metal has been poured into the mold.

It is desirable that the casting may be extracted from the mold immediately that congelation of the metal in a certain degree has taken place, and to enable this result to be achieved without loss of time is the principal purpose of my invention. The devices heretofore used for attaching dams to centrifugal molds have been somewhat complicated. It has not been possible to make the desired quick detachment, and much delay has been encountered by reason of the time required in the operations looking to the removal of the dam or cover from the mold.

My construction permits the dam or cover to be removed from the mold in a very brief period of time. It comprises devices which are adapted to connect and firmly retain the dam or cover in position during the casting operation, and which can be operated so as to bring about an immediate disconnection and permit instant removal of the dam or cover, and so afford access to the newly formed casting then in the mold and enable its withdrawal to be effected promptly.

Such devices are embodied in the provision upon the dam or cover of a series of pivoted latches which are operated into locking engagement with the mold, and which when so operated serve to firmly secure the dam or cover in position upon the mold. Reverse movement of the latches will break the connection and free the dam or cover for removal from the mold.

The latches are cam-actuated by means of slides also carried by the dam or cover, the slides being movable in one direction to effect the locking engagement, and in the other direction to break such engagement. The paths of movement of the slides are such that centrifugal force acting upon the said slides will tend to increase the locking of the parts during the casting operation.

Means are also provided for adjusting the parts comprising the dam or cover so as to

determine very accurately the manner of the engagement of the dam or cover with the mold.

In all former constructions of devices of the class to which the present invention relates, it was necessary in applying the dam or cover to the mold to bring the parts into a condition of accurate registry, in view of the fact that the co-operating attaching means upon the mold always bore a fixed relation thereto, and it was required that the like devices on the dam be aligned therewith before attachment could be made. But in my invention, the locking means carried by the dam are engageable with the mold in any position of the latter, so that the necessity for adjusting the parts to secure alignment and permit fastening is obviated.

The novel features of the invention will be pointed out in the appended claims.

In the accompanying drawing:

Figure 1 is a view in side elevation of a rotating mold, partly in section, and showing my improved devices in the position which they assume in locking the dam or cover to the mold.

Fig. 2 is a fragmentary view in the sectional plane of Fig. 1, and showing the said devices in the reverse or unlocking position.

Fig. 3 is an end elevation of the mold, viewed from the right in Fig. 1, and showing in section on the line 3—3, Fig. 1, parts of the construction.

Fig. 4 is a detailed sectional view on the line 4—4, Fig. 4.

Fig. 5 is a sectional view similar to Figs. 1 and 2, showing a slight modification in the construction.

Referring now to the drawing, the rotating tubular mold 10, open at one end, may be of usual form and mounting. At its mouth, and formed concentrically with the hollow of the mold, is a circular step 11, which receives a circular shoulder 12 upon the dam 13, the latter being in the general form of an annulus, and provided with a central opening through which the molten metal is introduced into the mold during the casting operation. The dam 13 is provided with a radial outer or circumferential flange 14, and supports a concentrically mounted ring 15. The latter is provided with a plurality of inwardly extending radial ears 16, into which are threaded the ends of screws

17, the heads of which are countersunk in openings in the flange 14, of the dam so as to draw the ring toward the dam. Other screws 18 are threaded into the flange 14 and bear at their inner ends with a thrust against the ears 16, so that an axial adjustment of the ring 15 with relation to the dam 13 may be secured and maintained.

10 Radially operating latches 19 of peculiar formation are mounted upon pins 20 set in the ears 16, transversely of the axis of the mold, the said latches 19 having the general form of bell cranks, the longer arm of which is provided upon its inner side with a catch 21 designed to take over a circumferential rib 22, formed exteriorly upon the mold 10 at the mouth thereof, which catches are adapted to be locked in engagement with the rib 22 when the latches are turned upon their pivots. Slides 23 are mounted in the rings 15 and are adapted to move longitudinally of the mold through the ears 16, such slides being provided upon their undersides with cams 24 which are adapted to move over the cam shaped ends 25 upon the outer sides of the latches 19. The short and outwardly projecting arm 26 of the latch or bell crank 19 is adapted to be struck by the heel of the cam 24 when the slide 23 is retracted, and so rotate the latch 19 upon its pivot as to disengage the catch 21 from the rib 22. This reverse movement of the slide 23 separates the cams 24 and 25 from their locking engagement, and frees the latch 19 for its outward movement of rotation when struck by the heel of the cam 24.

With the parts disposed as shown in Fig. 3, the dam 13 may be placed in position and secured to the mold 10 regardless of the relative positions of the parts, inasmuch as the said catches may take over the rib 22 in any position of the mold without the necessity for establishing a registering or definite rotary relation between the said catches and the rib on the mold.

40 The engaging faces of the cams 24 and 25 are inclined to the line of movement of the slide 23, so that when longitudinal movement is imparted to the slides by the application of pressure to the near or outer ends thereof, the cams 24 move over the cams 25 with a wedging action, and the result is the rotation of the latches 19 so as to engage the catches 21 with the rib 22 of the mold, and securely fasten or lock the dam in position upon the mold. With the cams in the position shown in Fig. 1, the frictional engagement is ordinarily sufficient to retain the parts. When it is desired to remove the dam 13 in order to permit extraction of the newly formed casting from the mold, it is necessary only to apply pressure to the opposite or inner ends of the slides 23, so that the cam 24 will be moved out of engagement with the cam 25. In such movement, the heel of the cam

24 strikes the short arm 26 of the latch 19, and rotates the latter, thus breaking the engagement of the catch 21 with the rib 22 upon the mold. The dam 13 may thereupon be removed.

70 The slides 23 are guided for movement in paths which diverge slightly from the axial line of the mold, to effect locking of the parts, the purpose of this arrangement being to utilize the centrifugal force exerted upon the said slides in the rotation of the mold as a means for further advancing the slides and holding the cams in engagement, thus negating any tendency to retraction during the casting operation.

75 Fig. 5 shows a simple modification in the relative proportions of the cam 24', the cam being somewhat reduced in length so as to permit a slight rocking movement of the latch 19 independently of the slide 23. 80 This arrangement may be used in case the weight of the longer arm of the pivoted latch in the construction shown in Fig. 1, is such as to overcome the frictional engagement of the slide with its guides. Should such action occur, the catch 21 would re-engage the rib 22, and the movement of the slide 23 might be such that the cam 24 would move back into engagement with the cam 25, thus locking the latch upon the ring 22. 85 But it will be seen from the construction shown in Fig. 5, in which an idle movement is provided for the cam 24', that the reverse movement of the latch 19 under the influence of gravity cannot move the slide 23 far enough to cause the cam 24' to engage the cam 25 on the said latch.

90 To prevent the latch 19 from over-running and swinging into an inoperative position, where it might contact with the front edge of the mold, it may be provided with a projection 27 which will act as a stop by engagement with the dam 13 at a suitable point upon the inside thereof. Such a projection is indicated in Fig. 5.

95 The construction may be simplified by forming the ring 15 with the ears 16 as integral parts of the dam, and omitting the provisions for adjustment.

100 Having thus described my invention, what I claim and desire to secure by Letters Patent of the United States, is:

1. In a centrifugal casting machine, a rotatable mold having an open end, a removable dam therefor, and means carried by the dam and adapted to secure the dam upon the mold in any position of the mold.

105 2. In a centrifugal casting machine, a mold having an open end, a removable dam therefor, and locking means carried by the dam and movable into engagement with the mold to secure the dam in closing position thereon.

110 3. In a centrifugal casting machine, a rotatable mold having an open end and pro-

vided with locking means, a dam for closing the mold, and co-operating locking means carried by the dam for securing the dam upon the mold.

4. In a centrifugal casting machine, a mold having an open end and provided exteriorly with locking means, a dam, and co-operating locking means carried by the dam for engaging the locking means first mentioned, to secure the dam upon the mold.

5. In a centrifugal casting machine, a mold having an open end and provided with a circumferential rib, a dam for closing the mold, a plurality of latches carried by the dam, and means for engaging the latches with the said rib to secure the dam upon the mold.

6. In a centrifugal casting machine, a mold having an open end and provided exteriorly with locking means, a dam for closing the mold, latches mounted upon the dam, and cams for actuating the latches into engagement with the locking means first mentioned to secure the dam upon the mold.

7. In a centrifugal casting machine, a mold having an open end and provided exteriorly with a circumferential rib, a dam, pivoted latches carried by the dam, and slides having cams adapted to move the latches into locking engagement with the said rib to secure the dam upon the mold.

8. In a centrifugal casting machine, a mold having an open end, a dam, an adjustable ring upon the dam, and means upon the ring for engaging the mold to lock the dam in closing position thereon.

9. In a centrifugal casting machine, a mold having an open end, a dam therefor, and radially movable means carried by the

dam for securing the latter in closing position upon the mold.

10. In a centrifugal casting machine, a mold having an open end, a dam therefor, movable means carried by the dam for connecting the dam to the mold, and means for actuating such connecting means.

11. In a centrifugal casting machine, a mold, a dam therefor, means for connecting the dam to the mold, and means carried by the dam and operating upon such connecting means to break the connection of the dam with the mold.

12. In a centrifugal casting machine, a mold, a dam therefor, means carried by the dam for connecting the dam to the mold, and means for acting upon the said connecting means to break the connection of the dam with the mold.

13. In a centrifugal casting machine, a mold, a dam therefor, movable means for connecting the dam to the mold, and devices for actuating such means into connecting position and by a reverse movement to break such connection.

14. In a centrifugal casting machine, a mold, a dam therefor, means carried by the dam for connecting the dam to the mold, and wedging devices for actuating said movable connecting means.

15. In a centrifugal casting machine, a mold, a dam therefor, movable means for connecting the dam to the mold, and wedging devices for actuating said movable connecting means.

In testimony whereof, I have signed my name at Milwaukee, this 12th day of November, 1924.

M. A. MIKESH.
